UNITED STATES PATENT OFFICE.

GRANT E. SMITH, OF POUGHKEEPSIE, NEW YORK.

DESIGN FOR AN AUTOMOBILE STEERING-WHEEL.

52,120.

Specification for Design.

Patented June 18, 1918.

Application filed January 22, 1917. Serial No. 143,870. Term of patent 14 years.

To all whom it may concern:

Be it known that I, GRANT E. SMITH, a citizen of the United States, residing at the city of Poughkeepsie, in the State of New York, have invented a new, original, and ornamental Design for Automobile Steering-Wheels, of which the following is a specification, reference being had to the accompanying drawing, forming part thereof.

Figure 1 is a plan view of an automobile

steering wheel showing my new design. Fig. 2 is an edge view.

I claim:

The ornamental design for an automobile steering wheel, as shown.

GRANT E. SMITH.
